UNITED STATES PATENT OFFICE.

EDUARD BERGMANN, OF VIENNA, AUSTRIA-HUNGARY.

HOLDER FOR TOOTHPICKS.

No. 800,787.

Specification of Letters Patent.

Patented Oct. 3, 1905.

Application filed October 12, 1904. Serial No. 228,236.

To all whom it may concern:

Be it known that I, EDUARD BERGMANN, first lieutenant in the Imperial Royal Austrian Army, a subject of the Emperor of Austria-Hungary, residing at IV Weyringergasse 40, in the city of Vienna, Austria-Hungary, have invented certain new and useful Improvements in Holders for Toothpicks; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has for its object a toothpick-holder which fulfills all hygienic requirements, owing to the fact that by its use the toothpicks are always kept in a completely-closed receptacle, from which only one toothpick at a time is raised and allowed to fall into a trough or the like, which is arranged outside the toothpick-receptacle and upon this latter.

Two constructional forms of carrying the invention into practice are illustrated in the accompanying drawings by way of example.

Figure 1 is an elevation. Fig. 2 is a cross-section through the middle of the appliance. Fig. 3 is a cross-section on the line A B of Fig. 4, and Fig. 4 is a longitudinal section of the first constructional form. Fig. 5 is a cross-section, on a reduced scale, through the middle of Fig. 7. Fig. 6 is a cross-section on the line C D of Fig. 7, and Fig. 7 is a longitudinal section of the second constructional form.

Referring to Figs. 1 to 4, the toothpick-holder consists of a circular glass body *a*, which presents a slot *b* upon one of its sides, while both its ends are mounted in an annular frame *c* of the stand *d*. The slot *b* of the glass body *a*, into which in the first constructional form a channel-shaped metal strip *e* extends, Fig. 2, which comes flush with the inner face of the glass body, is closed by an upwardly-displaceable slide *f*, which is maintained by means of the spring *g* in the closed position. This slide *f* is provided with two projections *h* at its two ends on the face directed toward the glass body, Fig. 3, on which an annular wire *i*, which slides in guides *k* of the frame *c* of the stand *d*, is fixed. This annular wire is connected at the other end with two projections *l* of a movable scoop *m* or the like and serves, on the one hand, to effect the guidance of the slide and, on the other hand, to operate the movable scoop. If the slide *f* is pushed up-

ward by means of the knob provided upon it, then owing to the intermediary of the annular wire *i* the movable scoop *m* also moves upward into the position indicated in broken lines, Fig. 2. In doing this the scoop seizes one of the toothpicks contained in the holder and lifts it until it arrives at the slot *b*, whereupon it falls through the slot into the channel *e*, formed by a metal strip. When the slide *f* is released, it is returned, under the influence of the spiral spring *g*, to its closed position, and the scoop *m* also returns to its initial position.

The ends of the glass body *a* are closed by caps *n*, which may advantageously be attached to the glass body by means of bayonet-joints.

In the constructional form of the device illustrated in Figs. 5 to 7 the slide or door *f* closing the slot *b* of the glass body *a* is connected with segments *o*, which are rotatably mounted upon the spindle *p*. A strip *q*, which is preferably of scoop shape, connects the two segments *o* one with the other and serves, on the one hand, for guiding these latter, and consequently the slide *f*, in guide-grooves *r* of the frame *c* and, on the other hand, for seizing a toothpick in order to raise the same when the slide rotates over the inner face of the container *a* up to the slot *b* in the glass body *a* and allows this pick to fall into the channel *s*, formed in or upon the base-plate for the container. If the slide *f* is hereupon released by the action of a spring *t*, it is returned to its closing position.

To prevent easy and mischievous insertion of soiled picks or dead matches into the receptacle when the cover or slide *f* is raised from over the aperture, I provide an obstruction consisting of a flange *a'*, formed on the upper and inner edge of the aperture *b*, as shown in Fig. 5. The lower edge of said flange being in the horizontal plane with the lower edge of the aperture will cause a match or pick inserted through the aperture to fall directly into the conveyer and be returned thereby when it is raised, and when the conveyer is in the raised position the slot is completely closed by the coöperation of the conveyer and flange.

Having now particularly described and ascertained the nature of my said invention and in what manner the same is to be performed, I declare that what I claim is—

1. A device of the character specified comprising a tubular body having a longitudinal slot therein, a casing on each end of said body,

- a carrying element in each casing, a conveyer secured to said carrying elements, and a slide on said carrying elements adapted to close the slot and operate the carrying elements.
- 5 2. A device of the character specified comprising a tubular body having a longitudinal slot therein, a casing on each end of said body, a carrying element mounted concentrically in each casing, a conveyer mounted on one end 10 of each carrying element, and a slide on the other end of each carrying element.
- 15 3. A device of the character specified comprising a tubular body having a longitudinal slot therein, a casing on each end of said body, a wire concentrically mounted in each casing, a conveyer in said tubular body mounted on one end of each wire, and a cover for the slot on the exterior of the body mounted on the other end of each wire.
- 20 4. A device of the character specified comprising a tubular body having a longitudinal slot therein, a casing mounted on each end of said body, a wire concentrically mounted in each casing, a plurality of guides for said 25 wires mounted in the casings, a conveyer with- in said body mounted on one end of each wire, a cover for the slot on the exterior of the body mounted on the other end of each wire and springs to normally hold the cover over the slot.
- 30 5. A device of the character specified comprising a tubular body having a longitudinal slot therein, a casing mounted on each end of said body, a plurality of guides mounted in each casing, a wire in each casing slidable in 35 said guides, a conveyer within the body, projections on the conveyer secured to one end of each wire, a cover for the slot on the exterior of the body, projections on the cover secured to the other end of each wire, a spring in each 40 casing interposed between the last-named projections and one of the guides, and a cap inclosing each casing.
- 45 In testimony that I claim the foregoing as my invention I have signed my name in presence of two subscribing witnesses.
- EDUARD BERGMANN.
